UNITED STATES PATENT OFFICE.

ISIDORE KRANZ, OF NEW YORK, N. Y.

DESIGN FOR A PENDANT FOR ELECTRIC-LIGHTING FIXTURES.

Application filed February 24, 1926. Serial No. 16,650. Term of patent 7 years.

To all whom it may concern:

Be it known that ISIDORE KRANZ, a citizen of the United States, and resident of New York, in the county of New York and State of New York, has invented a new, original, and ornamental Design for a Pendant for Electric-Lighting Fixtures, of which the following is a specification, reference being had to the accompanying drawing, forming part thereof, in which,

Fig. 1 is a view showing a pendant for

electric lighting fixtures embodying the invention.

Fig. 2 is a side elevational view thereof.

I claim:

The ornamental design for a pendant for electric lighting fixtures, as shown.

Dated, February 17, 1926.

Signed at New York, county of New York, State of New York.

ISIDORE KRANZ.
